Patented Dec. 23, 1924.

UNITED STATES PATENT OFFICE.

ELMER C. VON GLAHN AND EARL K. PECK, OF CORCORAN, CALIFORNIA.

TOY VEHICLE.

Application filed January 15, 1924. Serial No. 686,305.

To all whom it may concern:

Be it known that we, ELMER C. VON GLAHN and EARL PECK, citizens of the United States, residing at Corcoran, in the county of Kings and State of California, have invented certain new and useful Improvements in Toy Vehicles; and we do hereby declare the following to be a full, clear, and exact description of the invention, such as will enable others skilled in the art to which it appertains to make and use the same.

The present invention has relation to toys of the wheel type and provides a vehicle for children adapted to be propelled by foot power and in appearance simulating a flying machine of the biplane variety.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the spirit of the invention.

Referring to the accompanying drawings forming a part of the application:

Figure 1 is a side view of a toy vehicle embodying the invention,

Figure 2 is a view of the vehicle inverted, or as seen from the bottom side,

Figure 3 is a vertical central longitudinal sectional view of the vehicle, and

Figure 4 is a vertical transverse section on the line 4—4 of Figure 1, looking towards the front as designated by the arrows.

Corresponding and like parts are referred to in the following description and designated in the several views of the drawings by like reference characters.

The numeral 1 designates the body of the vehicle which in outline represents the fuselage of a flying machine and which in the present instance is preferably constructed of sheet metal pressed into the shape substantially as indicated. The body 1 is hollow and is closed at opposite sides and at the top and is open at the bottom, an opening being formed in the top for ingress and egress. An adjustable seat 2 is disposed within the body 1 in line with the opening in the top of the body, said seat being adjustable forwardly and rearwardly to adapt

its position to the size of the child so that its feet may reach the pedals of the crank shafts, whereby to propel or control the movements of the vehicle. The back 3 of the seat, as well as the rest 4, serves to stiffen and brace the body. Bolts 5 or analogous fastening means are provided to secure the seat 2 in the required adjusted position.

Braces 6 depend from the sides of the body 1 and a crank shaft 7 is mounted in their lower ends, the crank portions of the crank shaft being oppositely disposed and receiving pedals 8 which are adapted to be engaged by the feet of the child occupying the vehicle, whereby to propel the latter or control its movements.

An idle propeller 9 is loosely mounted upon a pin 10 projecting forwardly from the front end of the body 1. The propeller 9 is without function and materially adds to the appearance of the vehicle in representing a flying machine. The propeller rotates during the forward movement of the vehicle by impact of the air against the blades thereof.

Wings 11 project from opposite sides of the body and constitute the lower plane. An upper plane 12 extends across the body 1 and its ends terminate in line with the outer ends of the wings 11. Struts 13 connect the plane 12 and wings 11, thereby bracing these parts and supporting the plane 12.

Vanes 14 project from opposite sides of the tail portion of the body and a vertically disposed vane 15 operates between the rear extensions of the lateral vanes 14 and is attached to a vertical stem 16 which is provided at its lower end with a fork 17 in which is mounted a steering wheel 18. A crossbar 19, fixed to the stem 16 to turn therewith, has the outer end of one arm connected by means of a rod or stout wire 20 with the lower end of an operating lever 21 pivoted intermediate its ends to a side of the body 1 and disposed within convenient reach of the occupant of the vehicle. A similar connection 22 is attached to the outer end of the other arm of the crossbar 19 and extends forwardly and is slidably connected with the part 20 so as to move thereon.

The vehicle may be positively propelled by operating the crank shaft 7 in a manner well understood, or when coasting the movement may be controlled by means of the crank shaft, as will be readily appreciated.

Operation of the lever 21 controls the movements of the steering wheel 18 so that the direction of movement of the vehicle may be controlled. The movement of the steering wheel 18 in each direction is controlled by means of the vertical vane 15 and the rear extensions of the lateral vanes 14, said extensions constituting stops which are engaged by means of the vane 15.

10. What is claimed is:

1. A toy vehicle comprising a hollow body including spaced sides and a connecting top, the latter having an opening therein for ingress and egress, a block secured to each of the sides, each of said blocks having a longitudinal slot therein, a seat, securing means for the seat engaging said slots to permit adjustment forwardly and rearwardly, and

a rest and back comprising the seat and bracingly connecting the sides of the body. 20

2. In a toy vehicle, a steering wheel, a crossbar movable with the steering wheel, an operating lever, a connecting rod between an arm of the crossbar and said operating lever, and a similar connection attached to the other arm of the crossbar and slidingly engaging the connecting rod between the operating lever and crossbar. 25

In testimony whereof we affix our signatures in presence of two witnesses.

ELMER C. VON GLAHN.
EARL K. PECK.
